UNITED STATES PATENT OFFICE.

DOMINGO ANGLADA, OF NEW YORK, N. Y., ASSIGNOR TO WOLF SAFETY LAMP CO. OF AMERICA, INC., OF BROOKLYN, NEW YORK, A CORPORATION OF NEW YORK.

HANGER FOR LAMPS AND THE LIKE.

Application filed March 29, 1927. Serial No. 179,226.

This invention relates to hangers for lamps and is particularly useful in connection with miner's acetylene lamps.

Miner's acetylene lamps have been in use in coal and other mines for a great many years and are usually provided with a hook so that the miner may hang the lamp in proximity to the place at which he is working. Heretofore such lamps have been provided with a hook attached to a fixed eye riveted to a portion of the lamp. The constant engagement of the hook with the eye causes the eye to wear through resulting, in many cases, in the lamp falling and the open flame setting fire to the wooden shoring in the mine walls and ceiling. Further objection to the type of lamps heretofore in use resided in the fact that such lamps would swing on the eye and would, in many cases, be swung by accident to cause the acetylene flame to impinge upon the shoring resulting in fire. The present invention contemplates a solution of both of these problems.

In the drawings Fig. 1 is a perspective view of a miner's acetylene lamp provided with the subject of this invention; Fig. 2 is a top view of the lamp; Fig. 3 is a front view, partly in section, of the hanger and part of the handle of the lamp; Fig. 4 is a sectional view on the line 4—4 of Fig. 3; Fig. 5 is a sectional view on the line 5—5 of Fig. 3.

The lamp comprises the usual carbide chamber 1, a water reservoir 2, the burner 3 and reflector 4. The short arms 5 are welded to the top of the water reservoir 2 at opposite sides thereof and carry the ends 6 of the bracket 7 secured to the arms 5 by the rivets 8 so that the brackets 7 may be turned downwardly for convenience in packing the lamp.

The top cross-piece 9 of the brackets 7 is provided with spaced apertures 10 and 10^a leaving a section of metal therebetween which is punched downwardly to form the lip or bearing 11. The ring 12 is passed through the two holes 10 and 10^a and around the lip or bearing 11, the under side of which engages the inside of the ring. The

clearance for the ring 12 in the apertures 10 and 10^a is sufficient so that the ring may readily turn therein on the bearing 11. The hook 13 is secured to the ring 12 by threading the lower end thereof through the ring and bending the end over to form the eye 14.

In this construction the ring constitutes an anti-wearing device which will constantly change its position as the lamp is carried or as it swings, thereby exposing successive portions of the inner surface thereof for engagement with the eye 14 and the bearing 11 and thus avoids being worn through by constant friction with the eye 14 or the bearing 11 at a particular portion.

Further advantage of this construction resides in the fact that the lamp can swing but very little to the right and left on account of the absence of any great amount of play in the engagement of the ring with the apertures 10 and 10^a and with the eye 14. Various changes in the specific form shown and described may be made within the scope of the claims without departing from the spirit of my invention.

I claim:

1. In a lamp or the like a bracket, spaced apertures in the bracket, a ring passing through said apertures and movable therethrough, a suspending implement engaging with the ring, the ring being adapted to move freely and thereby expose successive portions thereof for engagement with the suspending implement.

2. In a lamp or the like a bracket, spaced apertures in the bracket, a bearing separating said apertures, a ring passing through said apertures and engaging at a portion of its inner surface against the under surface of said bearing, and adapted to move through said apertures to expose different portions thereof to said bearing.

3. In a lamp or the like a bracket, spaced apertures in the bracket, a bearing separating said apertures, a ring passing through said apertures and engaging at a portion of its inner surface against the under surface of said bearing and adapted to move through said apertures to expose different portions

thereof to said bearing, a suspending member passing through said ring and adapted to engage with successive portions thereof.

4. A lamp or the like provided with a bracket adapted to support the lamp, spaced apertures in the bracket, an anti-wearing member passing through said apertures and adapted to constantly shift its position as

the lamp is in use, to expose successive portions thereof to an implement on which it ^{is} hung to permit uniform wear of the member.

In testimony whereof I have hereunto set my hand.

DOMINGO ANGLADA.
